UNITED STATES PATENT OFFICE

145,024

DESIGN FOR A DISPLAY DEVICE FOR HOLDING FRUIT, CAKE, AND THE LIKE

Emil E. Hornung, Jacksonville, Fla.

Application July 20, 1945, Serial No. 120,817

Term of patent 3½ years

(Cl. D80—9)

To all whom it may concern:

Be it known that I, Emil E. Hornung, a citizen of the United States, residing at Jacksonville, in the county of Duval and State of Florida, have invented a new, original, and ornamental Design for a Display Device for Holding Fruit, Cake, and the like, of which the following is a specification, reference being had to the accompanying drawings, forming part thereof.

Figure 1 is a perspective view of a display device for holding fruit, cake, and the like showing my new design.

Figure 2 is a top plan view showing in detail those ornamental features visible when viewed in plan.

Figure 3 is an elevational view of one wall of the device showing in detail the ornamental features thereof.

Figure 4 is a view similar to Fig. 3 showing another wall of the container.

Figure 5 is a view similar to Fig. 4 showing another wall of the container.

Figure 6 is a view similar to Fig. 5 showing another wall of the container.

Figure 7 is a view similar to Fig. 6 showing another wall of the container.

Figure 8 is a view similar to Fig. 7 showing another wall of the container.

Figure 9 is a view similar to Fig. 8 showing another wall of the container.

Figure 10 is a view similar to Fig. 9 showing another wall of the container.

I claim:

The ornamental design for a display device for holding fruit, cake, and the like, as shown and described.

EMIL E. HORNUNG.
